United States Patent Office.

GEORGE A. LLOYD, OF SAN FRANCISCO, CALIFORNIA, ASSIGNOR TO HIMSELF AND ANTHONY ROSENFIELD.

Letters Patent No. 101,370, dated March 29, 1870.

IMPROVEMENT IN CARRIAGE-AXLES.

The Schedule referred to in these Letters Patent and making part of the same.

To all whom it may concern:

Be it known that I, GEORGE A. LLOYD, of the city and county of San Francisco, State of California, have invented certain new and useful Improvements in "Axles and Boxes for Vehicles," and I do hereby declare that the following is a full, clear, and exact description of the same, reference being had to the accompanying drawings and to the letters marked thereon.

My invention relates to the combination and arrangement of a double box, nut, and washer with the axle, in such a manner as to secure an automatic supply of the lubricating substance employed to all the wearing surfaces for a greater length of time, without attention or renewal of the supply of said lubricating substance, than has been hitherto possible in the use of similar devices, and also to attain a maximum of security against the collection of grit or dust between the surface and the sticking fast of the boxes to the axle.

The object of my invention is to provide a combined box and axle for vehicles that can be run for a maximum of distance or length of time without attention, and with a minimum of wear and liability to derangement.

To enable others skilled in the art or science to which it most nearly appertains to make and use my invention, I will proceed to describe fully its construction and operation.

In the drawings—

Figure 1, sheet 1, is an elevation representing the arrangement complete.

Figure 2, sheet 1, is a longitudinal section of the same.

Figure 3, sheet 1, is an end view from the left of fig. 1.

Figure 4, sheet 1, is an end view from the right of fig. 1.

Figure 1, sheet 2, is an end view of the inner box.

Figure 2, sheet 2, is a longitudinal section on the line *x x*, fig. 1.

Figure 3, sheet 2, is a longitudinal section on the line *y y*, fig. 1.

Like letters refer to like parts.

A is the axle.

B, the inner box.

C, the outer box.

D, the nut.

E, F, and G, the washers.

It is a well known fact that axles, as generally constructed, almost invariably break at or near the shoulder *a*.

To obviate this difficulty the axle A is much enlarged at that part, and the shoulder *a* is forged in one piece with the axle, and the whole finished or turned as shown in fig. 2, sheet 1.

The inner box B and outer box C are of such configuration as to correspond with and have a bearing upon the exterior surface of the enlarged part of the axle and upon the outer surface of the part forming the shoulder *a*, and upon each other, and when in position recesses or spaces are formed for collars or washers E, F, and G, and recesses or spaces *b b'*, for retaining a supply of the lubricating substance.

The inner box B is provided with perforations, recesses, and longitudinal grooves, for the same purpose, but differs from all others in having the enlarged or expanded parts *c c'*, bearing upon and effectually lubricating the corresponding parts of the outer box C and the axle A.

The form of the outer box also admits of having feathers, *d d'*, as shown, in such position as to be more easily fitted to, and affording greater security against turning in the hub, than is usual in boxes of ordinary construction.

By this construction the recesses and grooves in box B gather up and collect any dust or grit that may find its way to the bearing surface.

The washers E F G may be made of leather or some other suitable elastic substance, and serve the double purpose of preventing noise and also of preventing the entrance of grit or the escape of the lubricating substance to or from the wearing surfaces.

The nut D is firmly screwed against the shoulder *e*, and the washers E F G are made of just sufficient thickness to be slightly compressed by the said nut, and said washers must be occasionally renewed, as they become worn.

When in operation, the inner box B will usually revolve with the wheel or outer box C; but if, from the entrance of grit or any other cause, undue or excessive friction should arise between the box B and the axle, the box B would adhere to the axle, and the wheel and box C would revolve around both, and the wearing be transferred to the outer surface of box B and inner surface of box C.

Having thus described my invention,

What I claim, and desire to secure by Letters Patent, is—

In combination with the outer box C and axle A, having an enlargement and shoulder *a*, the inner box B, having the enlarged or expanded parts *c c'*, bearing upon and lubricating the outer box C and axle A, and forming recesses *b b'*, substantially as described and specified.

In testimony whereof I have hereunto set my hand and seal.

G. A. LLOYD. [L. S.]
